UNITED STATES PATENT OFFICE

EDWARD J. DEARY, OF BROOKLYN, NEW YORK, ASSIGNOR TO AUTOMATIC FIRE ALARM COMPANY, OF NEW YORK, N. Y., A CORPORATION OF NEW YORK

ALARM SIGNAL APPARATUS

Application filed April 6, 1926. Serial No. 100,028.

My invention relates particularly to apparatus for sending in signals electrically from various stations arranged on a common line.

The main object is to provide simple and reliable mechanism for sending in signals in such a manner that they will not interfere with each other.

The invention is directed particularly to what are commonly termed pull boxes. A number of these boxes are ordinarily arranged at various points in a building or plant intended to be protected and all of these boxes are connected by a common circuit to a central station of some sort. When trouble occurs adjacent any one of the sub-stations the nearest box is pulled or released. This box mechanism is then automatically driven to send in an alarm indicating the particular box which is operating. When a given box is operated, it automatically opens both arms of the line so that the subsequent operation of boxes further away from the central station will not send in any alarm until after the nearest box has completed its action, and also automatically puts a shunt or short circuit across the two outgoing wires, before the wires forming the circuit to the boxes farther away from the central office are opened, thus preventing any interference with signals at "central". When the nearest box completes its signal, the circuit is automatically restored to its initial position ready to transmit any signal which may come from any further station.

Fig. 1 is a rear view of one form of mechanism embodying my invention.

Fig. 2 is a view from the right hand edge of Fig. 1.

Fig. 3 is a view looking from the front with the front plate removed.

Fig. 4 is an edge view from the side opposite from that shown in Fig. 2.

All of the foregoing figures show the mechanism in the normal position of rest.

Fig. 5 is a detail view of the cut-out switch in action.

Fig. 6 is a perspective view of a cam member for operating the cut-out switch.

Fig. 7 is a diagrammatic view showing a system with two boxes, the one nearer the

central station being shown in the position in which it would be when the box is fully wound and showing how the farther box is cut-out by the action of the nearer box.

Although the invention relates primarily to an auxiliary switch and a method of operating it, I have shown and will describe the complete mechanism so that the operations may be better understood.

The main spring 10 has one end fixed or connected to the stationary stud 11 and the other end connected to the main shaft 12 so that the spring tends to drive or turn the main shaft in a clockwise direction as viewed from the rear in Fig. 1 or in anti-clockwise direction when viewed from the front.

The parts are all carried by a frame consisting of the front plate 13, the back plate 14 and connecting posts 15. The spring is held in place by an auxiliary plate 16.

The pull lever 17 is mounted on a shaft 18 which has a spring 19 on its rear end which spring tends to turn the handle 17 in a clockwise direction when viewed from the front. A lever 20 is secured to the shaft 18 and is normally pressed against the stop 21 by the action of the spring 19.

The pinion 22 on the shaft 12 meshes with a gear segment 23 carried by a sleeve 24 which is rotatable on the shaft 18. The lever 20 carries a pawl 25 which normally engages a pawl 26 carried by the gear segment 23, these pawls being both spring pressed toward the axis of the shaft 18. The gear segment 23 is normally pressed toward the abutment 21 by the action of the main spring 10.

The signal wheel 30 is carried by a shaft 31. The gear 32 on the main shaft 12 meshes with a pinion 33 which is rotatable on the shaft 31 and at times independently thereof. A ratchet wheel 34, having but one tooth, is secured to the pinion 33 so that they rotate together. The gear 35 which is secured to shaft 31 carries a spring pressed pawl 36 which normally engages the tooth of the ratchet 34. The wig-wag or vibrator 37 which controls the speed of the mechanism is operated by the toothed wheel 38. The pinion 39 secured to rotate with wheel 38 meshes with gear 35.

The usual signal switch or circuit breaker consists of a stationary contact member 40 and the movable contact member 41. The rotation of the signal wheel 30 operates the contact arm 41 to open and close the circuit in accordance with the number and arrangement of the teeth on the signal wheel. A second grounded signal wheel 30^a may be employed when a separate signal through ground is desired. These may be slightly out of step so as to produce the effect of staggered signals.

When it is desired to operate the box the lever 17 is pulled anti-clockwise as viewed from the front. This winds up the main spring and rotates the ratchet member 34 in an anti-clockwise direction as viewed from the front until the ratchet member 34 has made a complete revolution and its tooth again engages the pawl 36. When the pull lever 17 is released the spring 19 returns it to its normal position of rest as shown in the drawings. When the pawl 25 leaves the pawl 26 the latter tilts inwardly slightly under the impulse of its spring so that if the handle 17 is again pulled the pawl 25 will clear the pawl 26 and it will be impossible to interfere with the operation of the mechanism until the segment 23 and pawl 26 have returned to their normal positions. At the same time the main spring rotates the shaft 12, the gear 32, the pinion 33, ratchet 34, pawl 36, gear 35, the shaft 31 and signal wheel 30. At the same time the gear 22 on the main shaft 12 is returning the gear segment 23 to its normal position of rest. As the pawl 26 strikes the abutment 21 its tip is forced outwardly into position to be engaged by the pawl 25 on the operating lever 20.

Features of the structure above described are more fully described in the patent to Henry E. Reeve #1,697,140 dated Jan. 1, 1929.

The switch or cut-out which controls the circuit beyond the box consists of switch members 43, 44, 45, 46 and 47. The latter is carried by but insulated from an arm pivoted at 48 and normally held under tension of the spring 49 in the position shown in Fig. 1 so that the switch members 43 and 45 are in contact with each other and the switch members 44 and 46 are in contact with each other. On the rear end of the main shaft 12 I provide a sleeve 50 which rotates with the shaft both in the winding and unwinding movements. On this sleeve I mount an operating member which for convenience I will term a cam 51. This is preferably of insulating material and is connected to the sleeve in such a way as to permit the sleeve to have a limited freedom of movement with respect to the cam. This connection is effected by means of a pin 52 secured to the sleeve and projecting from one end as shown in Fig. 5 and a slot 53 in one side of the cam. The cam is provided with a notch or groove 54 in which a

finger or projection 55 on the switch member 47 normally rests as shown in Fig. 1, and in the upper part of Fig. 7 while the circuits are ordinarily closed through the switches. The cam also has one or more smaller notches 56 adapted to receive the finger 55 while the switch is still in the short circuited position of Fig. 5.

These smaller notches serve to yieldingly hold the cam while the alarm is being sent until the pin 52 reaches the end of the slot 53. The notches 56 are not necessary but serve to hold the cam while the pin 52 rotates in the slot.

In Fig. 7 I have shown diagrammatically a system with two boxes. The reference numbers on the lower box are those heretofore used in describing the details of the mechanism. The reference numerals on the parts of the upper box correspond with the others except that I have used the prime marks to distinguish. The elements are signal wheel 30', circuit breaker members 40' and 41', switch contacts 43', 44', 45', 46', switch member 47', spring 49', sleeve 50', cam 51', pin 52', groove 53', notch 54', finger 55' and notch 56'. The circuit includes a conductor 60, connected to switch member 43, conductor 61 which connects switch member 45 to the switch member 43', the conductor 62 connecting switch member 45' with the next box beyond (not shown). The central station may contain any suitable form of relay and annunciator mechanism such as R1 and R2 and batteries B; and the signal wheel of each box as well as the apparatus at the central station is grounded as usual in grounded circuit systems and as illustrated in Fig. 7 herein. The conductor 63 connects the central station with the circuit breaker contact 40. 41 is connected in the box with switch member 44 which normally is in contact with switch member 46. The latter is connected by a conductor 64 to a circuit breaker member 40' of the next box which is normally connected through the circuit breaker member 41' to the switch member 44'. The latter normally engages switch member 46' which is connected by conductor 65 to the next box beyond (not shown). The two sides of the line are connected to the various signal boxes and the conductors such as 62 and 65 from the last box in the line are connected together as indicated at X in Fig. 7 so that the entire system has a circuit which is normally closed thru the wires and the various signal boxes.

When the box is pulled the main spring is wound up and the shaft 12 and sleeve 50 are rotated anti-clockwise as viewed from the rear in Figs. 1 and 5 until the pin 52 engages what is the right hand end of slot 53 as viewed in Fig. 6. Continued rotation of the shaft 12 in winding up the spring rotates the cam with the pin 52 and sleeve 50 and

thus forcing the finger 55 out of the notch 54 and tilting the switch arm 47 into the position shown in Fig. 5 and in the bottom box of Fig. 7. This electrically connects the switch contacts 43 and 44 through the member 47 and at the same time separates them from the contacts 45 and 46.

It will thus be seen that both sides of the circuit of the next box beyond are broken by the separation of the switch member 43 from 45, and 44 from 46. No signal therefore which can subsequently come from the farther boxes will be transmitted to the central station. When the handle of the nearer box which has been pulled is released the driving spring of course starts to rotate the signal mechanism to send in the alarm, the circuit under these conditions extending through the conductor 63, circuit breaker members 40 and 41, switch members 44, 47, 43 and conductor 60. The shallow notch 56 in the cam 51 causes sufficient drag on the cam to prevent it from rotating by the mere frictional movement of the sleeve 50 within the cam so that the switch remains in the position shown in the lower part of Fig. 7 until the shaft 12, sleeve 50 and pin 52 have returned the cam to the position of Fig. 1 which is designed to occur after the signal has been completed. The cam is shown in its normal position at 51' in the top of Fig. 7. When the box is "pulled" (fully) the cam takes the position shown in the lower part of Fig. 7. When the box is "running" the sleeve 50 and pin 52 at one instant occupy the position of Fig. 5. The parts are so arranged that the box closest to the central office will always have control of the line when operating and positively cut out all boxes beyond it. The operation of the non-interfering device is not affected by a ground or open circuit on the main line since the signal circuit will always be completed through the signal wheel 30 and its ground return even though line 60 or 63 is broken. If the circuit were not broken between 46 and 44 and/or 45 and 43 when the inner or lower box is pulled any other box could send in its signal at the same time, thus causing great confusion.

The ground from the signal wheel 30 is necessary to complete the signal circuit in case either of the lines is broken. The normal circuit thru the apparatus when no signal is being sent may be traced from the central station thru the following elements: 60, 43, 45, 61, 43', 45', 62 to 65, 46', 44', 41', 40', 64, 46, 44, 41, 40, 63 to the central station.

When the box having the signal wheel 30 is pulled and the lines 60 and 63 are unbroken, the circuit will be traced from the central station thru 60, 43, 47, 44, 41, 40, 63 to the central station.

Each time a tooth of the signal wheel leaves

the contact member 41 from contact 40 a signal impulse will be sent to the central station. In case the line 60 is broken then the signal will be sent thru the circuit 63, 40, 41, 30 to ground. Similarly, if the line 63 is broken the circuit will run from central thru 60, 43, 47, 44, 41, 30 to ground and, of course, the signals are sent whenever the contact 41 snaps off of one of the teeth of the wheel 30. When one of these boxes is pulled, it is desirable to open both sides of the circuit—for instance, by separating 43 from 45 and 44 from 46.

This is necessary because if, for instance, 44 and 46 remained in contact while signal wheel 30 was sending an outer box could also be operated and its signal would be sent thru the circuit from ground to 30', 41', 40', 64, 46, 44, 41, 40, 63 to central and its usual ground.

We might thus have two signals being sent in at the same time or, at any rate, such of the signal of the outer box would be received as continued if the inner box had stopped operating which would confuse the signals.

I claim:

1. Mechanism of the character described comprising a shaft, a cam having a lost motion connection with said shaft, a switch arm operated by said cam, two pairs of switch members, the members of each pair being normally in contact with each other and the pairs being insulated from each other and a contact carried by said arm adapted to connect one member of each pair and simultaneously separate the members of each pair from each other, a code wheel driven with said shaft and contacts actuated by said code wheel and in circuit with said switch members.

2. Signal mechanism comprising a circuit breaker, a signal wheel for actuating said circuit breaker, a driving shaft, a switch arm, two pairs of switch members, the members of each pair being normally in contact with each other and the pairs being insulated from each other and a contact carried by said arm adapted to connect one member of each pair and separate the members of each pair from each other and means driven by said shaft for operating said switch arm and said signal wheel in sequence.

3. Signal mechanism comprising two pairs of switch members, the members of each pair being normally in electrical contact with each other, and one member of one pair being normally connected to one member of the other pair and the other members of the pairs being normally not connected with each other, a circuit breaker having two arms normally electrically connected, one of said arms being electrically connected to one of the switch members, a signal code wheel for actuating the latter arm to separate the arms, and mechanism for separating the members of the pairs of switch members and connecting the

members of the pairs which are normally not connected with each other before the signal code wheel actuates the circuit breaker and automatically restoring the switch members to normal circuit relation when the signal action is completed.

4. A grounded two-wire alarm apparatus comprising a series of box mechanisms each having a circuit breaker and two switches, one of said switches having two arms connected on one side of the line and the other switch having two arms connected on the other side of the line, all of the circuit breakers and all of the switches being normally connected in closed circuit relations, a signal wheel in each box for grounding one side of its circuit breaker and for separating the members of said circuit breaker, and mechanism in each box for opening both switches in said box in advance of the action of the signal wheel and electrically connecting one arm of each switch to one arm of the other switch and completing a signal path through the circuit breaker and closing both switches when the signal action is completed.

5. A normally closed two-wire grounded alarm system comprising a central station, a normally closed circuit leading therefrom comprising an outgoing and an incoming wire connected in series with a grounded source of energy, signal means in each of said wires, a plurality of box mechanisms interposed in said circuit each comprising two normally closed signalling contacts connected in series in one of said wires, in the portion thereof leading to the central station, a grounded code wheel having means for applying ground to said contacts and separating them, a switch comprising two normally closed contacts serially included in said one wire in the portion thereof leading to the box ahead, another switch comprising two normally closed contacts included in the other wire, means for separating the normally closed contacts of both of said switches and connecting the contact of the first switch which is connected to the code wheel operated contacts and the contact of the second switch which is connected to the portion of the wire leading towards the central station and means for first operating the separating and connecting means and thereafter operating the signal wheel.

EDWARD J. DEARY.
